UNITED STATES PATENT OFFICE.

CHARLES F. MASSEY, OF CHICAGO, ILLINOIS.

DESIGN FOR A PORTABLE CONCRETE HOUSE.

44,017.

Specification for Design.

Patented May 13, 1913.

Application filed December 19, 1912. Serial No. 737,739. Term of patent 7 years.

To all whom it may concern:

Be it known that I, CHARLES F. MASSEY, a citizen of the United States, residing at Chicago, in the county of Cook and State of Illinois, have invented a new, original, and ornamental Design for Portable Concrete Houses, of which the following is a specification, reference being had to the accompanying drawing, forming part thereof.

The figure is a perspective view of a portable concrete house, showing my new design.

I claim:

The ornamental design for a portable concrete house, as shown.

CHARLES F. MASSEY.
